UNITED STATES PATENT OFFICE

2,447,846

CAR DOOR

Frank Ditchfield, Cleveland, Ohio, assignor to
The Youngstown Steel Door Company, Cleve-
land, Ohio, a corporation of Ohio

Application September 25, 1944, Serial No. 555,684

4 Claims. (Cl. 20—22)

1

This invention relates to car doors.

It is the main object of this invention to provide a construction for the lower portions of sliding car doors which shall eliminate the entry of direct and reflected light and prevent snow, rain, dust, cinders and the like from being forced upwardly into the cars through the door openings therein.

A further object is to provide a construction for the lower portions of sliding lift car doors which shall eliminate the entry of direct and reflected light and prevent snow, rain, dust, cinders and the like from being forced upwardly into the cars through the door openings therein without interfering with the lifting and opening and closing movements of the doors.

Other objects of the invention will become clear as the description thereof proceeds.

In the drawings forming part of this specification:

Fig. 1 is a fragmentary elevation of a sliding lift door utilizing the instant invention, the door being shown in lowered position and the lift mechanism therefor being omitted for the sake of clarity.

Fig. 2 is a vertical section taken on line 2—2 of Fig. 1.

Fig. 3 is a vertical section similar to Fig. 2, the door being shown in raised position.

Fig. 4 is a horizontal section taken on line 4—4 of Fig. 1.

Referring to the drawings wherein a preferred embodiment of the invention is illustrated, the numeral 10 designates the side sill of a railway house car. The side sill is reinforced as more clearly shown in Figs. 2 and 3 of the drawings by means of a bulb angle 11. Front and rear door posts 12 and 13 are secured to the side sill 10 and define the width of a door opening 14 formed in each wall of the car. A front door stop 15 is secured to the front door post 12. A post protection angle 16 to which a spark strip 17 is secured as more clearly shown in Fig. 4 of the drawings, is fastened to the rear door post 13.

A door track 18 is secured below the door opening 14 to the side sill reinforcement 11 by means of a plurality of track brackets 19. The door track 18 is adapted to support a door 20 which controls the door opening 14.

The door 20 may be of any desired construction but as illustrated it is formed of metal and embodies a metallic panel 21 formed with a plurality of horizontal corrugations, one of which is indicated at 22. The margins of the metallic panel 21 are suitably reinforced as is well known

2

in the art. The reinforcement for the upper margin of the panel is not shown. The reinforcement for the front vertical margin is indicated generally at 23. The reinforcement for the rear vertical margin of the panel is illustrated in Fig. 4 of the drawings and takes the form of a substantially W-shaped plate 24 to one flange of which a sealing strip 25 is fastened. The sealing strip cooperates with the spark strip 17 to provide a seal for the rear vertical margin of the door.

The lower horizontal margin of the metallic panel is reinforced by means of a T-shaped member 26 which is preferably a rolled structural shape. The reinforcing member 26 is secured to the metallic panel by disposing one flange 27 thereof between the metallic panel and a reinforcing backing plate 28 therefor and securing said flange in such position as by means of rivets 29. The stem 30 of the T-shaped reinforcing member 26 extends outwardly and the remaining flange 31 of said member extends downwardly.

As more clearly illustrated in Fig. 2 of the drawings, the outwardly extending stem 30 of the reinforcing member 26 is utilized to establish frictional support of the door upon the track 18 when the door is in lowered position and in cooperation with the track to prevent foreign matter from being blown into the car through the door opening from the outside of the door. Moreover, the depending flange 31 of the T-shaped reinforcing member 26 lies behind the track 18 and cooperates therewith both in the lowered and raised positions of the door to prevent accidental disengagement of the door from the track. The depending flange 31 also is utilized in cooperation with a threshold plate 32 to further preclude the entry of foreign matter into the car and to prevent the entry of direct and reflected light without in any way interfering with the raising or opening and closing movements of the door.

As clearly appears in Figs. 2 and 3 of the drawings, the threshold plate lies flatwise upon the floor 33 of the car and is conventionally fastened thereto and to the side sill and side sill reinforcement by means of bolts (not shown). The threshold plate projects outwardly beyond the side sill 10 and for this purpose the side sill is coped as indicated at 34 in the door opening 14. The projecting portion of the threshold plate 32 is supported by means of an angle member 35 which is secured to the sill as by means of rivets 36. Beyond the supporting angle 35 and between the door posts 12 and 13 the threshold plate is flanged downwardly as shown at

37. Angle clips 38 are secured to the threshold plate flange 37 as by means of welding and are disposed in abutment with the underside of the supporting angle 35 in order to retain the threshold plate against upward movement. The forward flange 37 of the threshold plate terminates in an outwardly projecting flange or lip 39 which extends across and beyond the flange 31 of the T-shaped door reinforcing member 26 and lies adjacent to the lower edge of the flange 31 when the door is in lowered position. This relationship between the flange 31 of the reinforcing member 26 and the outwardly projecting lip 39 of the threshold plate effectively prevents direct and reflected light from entering the car and provides an effective baffle for preventing foreign matter from being blown upwardly into the car between the door and the depending vertical flange 37 of the threshold plate. With reference to Figs. 2 and 3 of the drawings, it will be apparent that while the stated purposes are obtained by means of the construction hereinabove described, lifting and opening and closing movements of the door are in nowise interfered with.

The effectiveness of the hereinabove described relationship between the threshold plate and the T-shaped door reinforcing member is enhanced by the extension of the lip 39 on the threshold plate forwardly and rearwardly of the door posts 12 and 13 as indicated at 40 and 41 in Fig. 4 of the drawings. The forward extension 40 of the lip 39 terminates at the front stop 15 and the rearward extension 41 of the lip 39 terminates substantially in line with the outer edge of the spark strip 17.

The door is shown in its lowered position when it is frictionally supported by the track 18 in Fig. 2 of the drawings. In Fig. 3 of the drawings the door is illustrated after it has been raised so that it is in position for opening or closing movement. In order to raise and support the door for movement upon the track 18 the lift mechanism illustrated in applicant's co-pending application Serial No. 465,233, filed November 11, 1942, (now Patent No. 2,415,731, granted February 11, 1947) may be utilized, or where lift mechanism secured to the lower portion of the door is preferred, the lift mechanism illustrated in the patent to Madland, 2,027,242, granted January 7, 1936, may be employed.

This application is a division of applicant's co-pending application above identified.

It will be apparent that numerous changes and modifications in the details of the invention will be clear to those skilled in the art. It is intended, therefore, that all such modifications and changes be comprehended within this invention, which is to be limited only by the scope of the claims appended hereto. While the instant invention is illustrated and described in connection with a lift door, it is apparent that it may also be utilized in connection with straight sliding doors.

I claim:

1. In a railway house car having a door opening in a wall thereof and a floor, a track secured to said car below said door opening, a door slidably mounted on said track, the lower portion of said door lying behind said track, and a threshold plate secured to said floor in said door opening, said threshold plate having a flange extending downwardly below said door opening in outwardly

spaced relation to said floor and contiguous to the inner face of said door when the latter is closed and a lip extending outwardly from said flange, said lip extending across and adjacent to the lower edge of said door when the door is closed, for the purpose set forth.

2. In a railway house car having a door opening in a wall thereof and a floor, a track secured to said car below said door opening, a door slidably mounted on said track, the lower portion of said door lying behind said track, and a threshold plate secured to said floor in said door opening, said threshold plate having a flange extending downwardly below said door opening in outwardly spaced relation to said floor and contiguous to the inner face of said door when the latter is closed and a lip extending outwardly from said flange, said lip extending forwardly and rearwardly of said door opening and across and adjacent to the lower edge of said door when the door is closed, for the purpose set forth.

3. In a railway house car having a door opening in a wall thereof and a floor, a track secured to said car below said door opening, a lift door slidably mounted on said track, the lower portion of said door lying behind said track, and a threshold plate secured to said floor in said door opening, said threshold plate having a flange extending downwardly below said door opening in outwardly spaced relation to said floor and contiguous to the inner face of said door when the latter is closed and a lip extending outwardly from said flange, said lip extending across and adjacent to the lower edge of said door when the door is closed, said door being adapted to be raised for opening and closing movements so that the lower edge thereof lies a substantial distance above said lip whereby said lip does not interfere with said movements of said door.

4. In a railway house car having a door opening in a wall thereof and a floor, a track secured to said car below said door opening in spaced relationship to said car, a door slidably mounted on said track, the lower portion of said door lying behind said track, and a threshold plate secured to said floor in said door opening, said threshold plate having a flange extending downwardly below said door opening in outwardly spaced relation to said floor and contiguous to the inner face of said door when the latter is closed and a lip extending outwardly from said flange, said lip extending across and adjacent to the lower edge of said door when the door is closed, for the purpose set forth.

FRANK DITCHFIELD.
